UNITED STATES PATENT OFFICE.

WILLIAM HENRY SUMBLING, OF TORONTO, ONTARIO, CANADA.

IRONING MACHINE.

Application filed March 6, 1926. Serial No. 92,926.

My invention relates to improvements in ironing machines, otherwise known as mangles, and relates more particularly to improvements in machines of the class set forth in which the shoe or buck is fixed, and wherein unobstructed access is had between one end of the roll, and the shoe or buck, and the objects of my invention are: 1, to equalize or differentiate the pressure of the roll against the shoe or buck.

2, to permit of the roll while still in gear, being moved through means under the control of the foot, away from the shoe or buck in order to facilitate the manipulation of the work.

3, to throw the roll completely out of gear to provide for ease of replacement of the covering.

4, to movably mount the feed board to permit the same to be moved out of the way when it is desired to iron such articles as skirts.

5, to simplify the construction of machines of this class by providing only one set of spring-controlled locking means which function to maintain the roll under pressure against the shoe or buck, and in the following specification and the drawings forming part thereof, I shall describe and illustrate a disclosure within my invention, and what I claim as new will be set forth in the claims forming part of this specification.

Fig. 1 is an elevation of one end of the machine, showing the roll spring-held against the shoe or buck, and Fig. 2 is an elevation of the other end of the machine, with the roll in the same position. Fig. 3 is an elevation of the rear side of the machine. Fig. 4 is an elevation of the same end of the machine as shown in Fig. 1, but showing the roll away from the shoe or buck and out of gear. Fig. 5 is an elevation of one end of the major portion of the front side of the machine. Fig. 6 is a vertical longitudinal section on the line 6—6, Fig. 2. Fig. 7 is a horizontal section on the line 7—7, Fig. 2. Fig. 8 is a horizontal section on the line 8—8, Fig. 1, and Fig. 9 is a plan view of portion of the end of the machine shown in Fig. 2, showing the support for the feed

board out of normal position to permit free access between the end of the roll and the shoe or buck when ironing skirts, for example: this view shows the roll away from the shoe or buck.

In the drawings, like characters of reference refer to the same parts.

In using machines of this class, it is very important that both hands of the operator be available to manipulate the goods, while the roll is yieldingly held against the shoe or buck, and as will hereinafter appear, the spring-controlled means used to maintain the roll against the shoe or buck is bi-functional in character so that while the roll is still in gear, it may be moved under the control of the foot sufficiently away from the shoe or buck to permit of the manipulation of the work, and without the necessity of having to stop the motive power for the machine.

The frame of the machine may be of any desired construction, and is conveniently illustrated in the form of standards 2 with which are preferably integrally formed cross pieces 3 and 4 which tie the upper ends of the standards 2 together at different ends of the machine. 5 is the electric motor used preferably to drive this machine, though of course any suitable motive power may be used. This motor through the means of the belt 6 drives the shaft 7 through the medium of the pulley 8 thereof. The driving means just described may be enclosed in any suitable housing 9. The shaft 7 is housed within any suitable tubular member 10, and is provided with a worm 11 mounted within the boxing *a*, which worm meshes with the worm heel 12 mounted on the stud 13, through the medium of the hub *b* of the pinion 14, also mounted on the stud 13. This pinion in turn drives a gear wheel 15 which is keyed to the shaft 16. The stud 13 is held in the vertical plate *c* of the frame of the machine.

17 is an arm with which is integrally formed the head 18, and it is through this head the shaft 16 passes. The head 18 extends well into the roll 19, and for convenience of manufacture, this head is extended well towards the outer end of the roll

19 by means of a tubular extension 20 which is fixedly mounted within the head 18. Of course if desired, the tubular extension 20 may be integrally formed with the head 18. Since the head 18 does not rotate around its axis, suitable bearing means must be provided for the shaft 16. Suitable anti-friction means for this purpose is shown at 21, at one end of the shaft 16, and near the other end of the shaft suitable anti-friction means 22 is shown. This latter anti-friction means is interposed between the tubular extension 20 and a housing 23, which housing is suitably fixed to the roll 19. 24 is a cap mounted on the outer end of the shaft 16, and suitably secured thereto as by means of a set screw 25. The cap 24 is suitably coupled to the housing 23 by any suitable means such as a screw 26. By the means just described, movement is transmitted from the shaft 16 to the roll 19.

To provide bearing for the roll 19 adjacent the head 18 a housing and cap and anti-friction means similar to those just described 25 are provided and are collectively indicated at 27.

The vertical plate *c* is slotted as shown at 28, and through this slot extends the outer end of the head 18. The gear wheel 15 is 30 located at the outer side of the plate *c*.

The vertical plate *c* at one end of the machine, and a vertically-disposed plate *d* at the other end of the machine (see Figs. 2 and 4) support the shoe or buck 29 which is 35 conventionally shown. This shoe or buck is heated in any suitable manner, and since the means for this purpose forms no part of my invention, I have not illustrated the same.

Integrally formed with the lower end of 10 the arm 17 and extending in the same direction as the roll 19 is a tubular extension 30, and passing through this tubular extension is a rock-shaft 31 which is suitably coupled to said tubular extension as by means of 15 a set screw 32. This rock-shaft extends beyond each end of said tubular extension, and at one end of the machine it is journaled in a block 33, which block is mounted in a slot 34 formed in the cross piece 3: 20 this construction supports this end of the rock-shaft 31. 35 is a pin which passes through a hole formed in the block 33 and is tapped into the cross piece 3 at its upper end: the lower end of this pin is held in the 25 cross piece 3. The construction just described, or its equivalent, provides for horizontal movement of the tubular extension 30 and the rock-shaft 31, for the purpose hereinafter more particularly explained. It will 30 be seen upon reference particularly to Figs. 1 and 4, that the block 33 has clearance with each end of the slot 34.

The outer end of the rock-shaft 31 is journaled in a block 36, which is mounted in 35 the slot 37 formed in the cross piece 4. 38 is

a housing the inner side of which is slotted as shown at 39 and through which extends the outer end of the rock-shaft 31. This housing is substantially U-shaped in horizontal section, and the inner ends of the U 70 are bolted to the cross piece 4 as shown at 40. The cross piece 4 is provided with an inwardly extending flange 41, and against this flange rests a coiled spring 42. The other end of this spring receives a boss 43 carried 75 by the block 36, and is so kept in position. 44 is an adjusting screw threaded through the front wall of the housing 38, and adapted to be held in contact with the block 36. This screw may be, if desired, provided with 80 a handle or lever 45 to manipulate the same. 46 is a nut mounted on the adjusting screw 44 and adapted to lock it in adjusted position, if desired.

Integrally formed with the tubular extension 30 are arms 47, and in the outer end of each of these arms is pivoted a link rod 48. 49 is a treadle conveniently mounted in the lower portion of the standards 2. For example, the treadle may be mounted on a 90 rock bar 50 which is conveniently held in the standards 2. This treadle is slotted as shown at 51 (see Fig. 1) where each link rod 48 passes therethrough, and these slots are of sufficient size, and the desired shape, 95 to permit of the movement of said treadle without binding against the link rods 48, the lower end of each of which is provided with a nut 52, or other stop which permits the treadle to be brought into engagement 100 therewith to actuate the same.

Carried by, or integrally formed with the arm 17, is an arm 53, the location of which may be varied, though for convenience in construction this arm is located at that end 105 of the machine supporting the driving gear. Extending through this arm is a rod 54, the lower end of which is threaded and is provided with a nut 55 which normally rests in contact with the underside of the arm 53. The upper end of this rod 54 is threaded or otherwise fixedly associated with a jaw 56. In this jaw is pivoted an arm 57 by means of the pin 58. The arm 57 is carried by a hub 59, which hub is secured by any suitable 110 means such as a set screw 60 to the shaft 61 which has bearing in the arm 62 carried by the vertical plate *c* (see Figs. 1 and 2). 63 is a lever mounted on the shaft 61 and suitably coupled thereto as by means of a 115 set screw 64.

Mounted on the rod 54 is a coiled spring 65, and tension of this spring is regulated by the nut 66 threaded on the upper end of the rod 54.

While the parts, per se, just described are old in the art, still, as far as I know, the prior art does not disclose this pressure-controlling means in its simplicity, that is to say, two pressure-controlling means of the 130

character described have heretofore been considered necessary in this type of machine, whereas I find I need only use one unit.

Having now described the principal parts of my machine, I shall describe its operation.

As before-noted, any suitable type of motive power may be used to drive the roll, and in order to get the best results from a machine of this class, the operator's both hands must be free to manipulate the work.

Before the work is to be operated on, the lever 63 is moved from the position shown in Fig. 4 into the position shown very clearly 15 in Figs. 1 and 2 with the stop *e* in contact with the arm 62. Now since the arm 57 is coupled to the shaft 61, the movement of the lever 63 moves this arm in the direction indicated by the arrow in Fig. 4, and since the 20 rod 54 is pivoted to the arm 57, this movement causes the rod 54 to slide through the arm 53, with result that the spring 65 is compressed, and motion is conveyed through the arm 17 to the head 18 (see Fig. 6) with the 25 result that the roll 19 is brought into contact with the shoe or buck 29 (see Fig. 2).

The roll 19 is locked in the position described from the fact that when the parts are in the position shown particularly in 30 Figs. 1 and 2, a vertical line passing through the axis of the shaft 61 will be nearer the machine than a vertical line passing through the pin 58, and the result is that the spring 65 will, through the leverage provided for 35 the arm 57 under the conditions noted, lock the lever 63 in the position shown in Figs. 1 and 2. The position of the parts just described will also yieldingly hold the roll 19, through the medium of the arms 53 and 17 40 in contact with the shoe or buck 29.

The work is fed over the feed board 67 between the shoe or buck 29 and the roll, and since this roll is spring held against the said shoe or buck, it will automatically move to 45 accommodate itself to the different thicknesses of the work.

This automatic yielding action of the roll, and the means to hold the roll yieldingly in position against the shoe or buck 29, 50 is of course known in the art, but the means I employ to transmit motion from the lever 63 and spring 65 to the roll, is new.

Should the operator be required to adjust the work, this can be done without moving 55 the lever 63, by pressing down upon the treadle 49. The treadle coming in contact with the nuts 52 will through the medium of the link rods 48 and arms 47 turn the tubular extension 30 on the rock-shaft 31: this 60 movement will be transmitted through the arm 17 to the head 18, and result in the moving of the roll 19 into the position shown by dotted lines in Fig. 2. While the parts described are in the dotted positions shown, the 65 spring 65 of course is under greater com-

pression than when it occupies the positions shown in Fig. 1.

Upon removal of pressure against the treadle 49, the spring 65 will expand and move the parts from dotted position shown 70 in Fig. 2 into the position shown in full lines in this figure.

In moving the roll 19 away from the shoe or buck 29 under the conditions previously described, it is not necessary to stop the motive power, nor is it necessary that the pinion 14 be out of mesh with the gear wheel 15. 75

The feed board 67 is of any convenient construction, and it is conveniently hinged as shown at 68 to the upper portion of the vertical plate *c*. The outer end is supported by a leg or support 69 which is hinged as shown at 70 to the table 71, which table is supported by the standards. 80

When the feed board 67 is moved into the dotted position shown in Fig. 3, the leg or support 69 drops down into the dotted position shown in this figure, and consequently unobstructed access is had to the outer end of the roll 19 and the shoe or buck 29 (see Fig. 9), so that when the roll is moved away from the co-operating surface of said shoe or buck, garments such as skirts may be positioned to be ironed: this is an important 90 feature of my invention. 95

In order to hold the feed board 67 in the vertical dotted position shown in Fig. 3, it is provided with any suitable counter-weight 72. 100

When the lever 63 is in the position shown in Fig. 4, through the co-operation therewith of the arm 57, rod 54, arm 53, tubular extension 30, arm 17, and head 18, the roll 19 is moved into the position shown in this figure so that its gear wheel 15 will be out of mesh with the pinion 14: the result is that although the motive power may be in action, the said roll may be rotated as desired in order to replace the cover, or for any other desired purpose. 110

The means shown to throw the roll 19 out of gear is very simple, yet positive in action, and is the same used to move the spring-held roll out of contact with the shoe or buck 29 when adjusting the work, as shown in Fig. 2. Obviously when the lever 63 is moved into the position shown in Fig. 1, the gear wheel 15 is brought into mesh with the pinion 14. 115

The parts controlling the movements of the roll 19 throughout its length, substantially equal distances towards and away from the shoe or buck 29, essentially move the axis of this roll through a vertical plane, and I shall now describe the action of means used to adjust the said roll by moving its axis 120 through a horizontal plane.

As before-mentioned, the outer end of the rock-shaft 31 is journalled in a block 36, and upon referring particularly to Fig. 3, it will be seen that the said rock-shaft 31 is prac- 125

1 tically of the same length as the axis of the roll 19, thereby ensuring the proper leverage. Since the block 36 may be moved inwardly in the slot 37 through the medium of the adjusting screw 44, such movement of this block will move the rock-shaft 31, and cause the block 33 to move around the pin 35; this movement will be transmitted to the tubular extension 30, and through this extension and the arm 17 to the head 18, and through the tubular extension 20 to the outer end of the roll 19. When the desired pressure is provided at the outer end of said roll, the adjusting screw 44 may be locked in position.

During the described movement of the block 36, the spring 42 is of course additionally compressed, and should it be desired to reduce the pressure of the outer end of said roll against the shoe or buck, when the adjusting screw 44 is retracted, the spring 42 will exert pressure to move the block 36 outwardly and, through the parts already clearly described, the outer end of the roll 19 will be moved away from said shoe or buck.

Anti-friction means will wear in time, and if it were only because of this fact alone, the means I disclose, or the equivalent thereof, operating in the manner set forth, would be necessary in association with the roll 19 to produce a machine of the class set forth of the highest efficiency: therefore it is self-evident that said adjusting means will be used to take up wear in the bearings, and also to increase or decrease the pressure of the outer end of the roll 19 against the shoe or buck, accordingly as the operator may desire.

40 But it must be understood that if this machine be used upon work of a uniform thickness, for all practical purposes, there would be no necessity of providing means to move the roll 19 through a horizontal plane, therefore I do not necessarily confine myself to using such means.

While the movements described to be given to the outer end of the roll 19 are appreciable, the movements of the inner ends of the shaft 16 and rock-shaft 31 are not sufficient to interfere with the efficient co-operation of the gear wheel 15 and pinion 14.

Furthermore since the treadle 49 is slotted where the link rods pass therethrough, these link rods will not bind with the said treadle and interfere with the horizontal movement just described.

If desired, I may provide the lever 63 with a shield 75 which, when the parts are in the position shown in Fig. 1, would prevent access to the switch mechanism 76; this switch mechanism will only be uncovered fully when the lever 63 is moved into the position shown in Fig. 4; this makes for safety in operation.

70 While I may use any source of heat for the buck or shoe, in localities where electric current is available this is used to heat the buck. Some switch mechanism must be employed to control the current for this purpose, and in Figs. 1 and 3 I show a suitable switch, which embraces the casing 80 suitably supported. This casing is provided with an outlet 81, and a switch 82. It is further provided with an opening covered 75 with a piece of red glass 83 through which an electric bulb (not shown) can be seen to visually indicate when the current is on.

75 From the foregoing part of the specification, it will be seen that in a machine of the class set forth where the shoe or buck is fixed, and the roll movable to or away therefrom, I have provided interrelated groups of elements providing for independent adjustments of the said roll through vertical 80 and horizontal planes; but it must be distinctly understood that although I have described and illustrated a specific embodiment of my invention, I do not confine myself thereto and desire not to be limited in my 85 scope of protection beyond the requirements of the prior art and the terms of my claims.

90 What I claim as my invention is:

1. In a machine of the class described, in combination, a roll; internally-located supporting-bearing means therefor projecting beyond one end only thereof; driven means located within said supporting-bearing means, and projecting beyond said end only of the roll, and whereby said roll is revolved; a frame; means whereby the said supporting-bearing means is horizontally pivoted in said frame below said roll; a fixed shoe supported by said frame adjacent said roll, and spring-provided lever mechanism to dominate the position of said roll with respect to said shoe through the means of said supporting-bearing means. 100

105 2. In a machine of the class described, in combination, a roll; internally-located supporting-bearing means therefor projecting beyond one end only thereof; driven means located within said supporting-bearing means, and projecting beyond said end only of the roll, and whereby said roll is revolved; a frame; means whereby said supporting-bearing means is horizontally pivoted in said frame below said roll; a fixed shoe supported by said frame adjacent said roll; a spring-provided lever mechanism to dominate the position of said roll with respect to said shoe through the means of said sup- 110

115 porting-bearing means, and a treadle coupled to the pivoting means for said supporting-bearing means to move the roll away 120 from the shoe in opposition to the action of said lever mechanism. 125

130 3. In a machine of the class described, in combination, a roll; internally-located supporting-bearing means therefor projecting

- beyond one end only thereof; driven means located within said supporting-bearing means, and projecting beyond the outer end of said supporting-bearing means; a gear 5 wheel keyed to the outer end of said driven means; a frame, the same being provided in its upper portion with a slot through which the outer end of said supporting-bearing means passes; a stud fixedly supported 10 by said upper portion of the frame, and on which is journalled a pinion normally in mesh with said gear wheel; a vertically-disposed arm fixedly associated with said supporting-bearing means and located beyond 15 the inner end of said roll; a horizontally-disposed member fixedly associated with the lower end of said arm; means whereby said member is journalled at each end in said frame so as to be movable on its axis; an 20 arm fixedly associated with said horizontally-disposed member; a spring-provided lever mechanism pivoted to said frame and connected with the outer end of said arm, and used to dominate the position of said roll 25 with respect to that of said shoe; a pair of arms fixedly associated with said horizontally-disposed member; a link rod pivoted at its upper end to each of said second-mentioned arms, and a treadle pivoted in the 30 lower portion of said frame and with which the lower ends of each of the said link rods co-operate to permit said supporting-bearing means to be moved to remove the roll away from the shoe in opposition to the action of said lever mechanism. 35
4. In a machine of the class described, in combination, a roll; internally-located supporting-bearing means therefor projecting beyond one end only thereof; driven means located within said supporting-bearing means, and projecting beyond the outer end of said supporting-bearing means; a gear wheel keyed to the outer end of said driven means; a frame, the same being provided 40 in its upper portion with a slot through which the outer end of said supporting-bearing means passes; a stud fixedly supported by said upper portion of the frame, and on which is journalled a pinion normally in mesh with said gear wheel; a vertically-disposed arm fixedly associated with said supporting-bearing means and located beyond the inner end of said roll; a horizontally-disposed member fixedly associated 45 with the lower end of said arm; a rock-shaft located within said member and keyed thereto, and projecting beyond each end thereof; a bearing block for each outer end of said rock-shaft, each bearing block being located 50 in a slotted portion of each end of the frame; means whereby one of said bearing blocks is pivoted in place to one side of said rock-shaft to permit the same to be moved in a horizontal plane; pressure-regulating means 55 associated with said other block whereby 60 through the movement of said rock-shaft in a horizontal plane the position of the outer end of said roll with respect to that of said shoe can be regulated. 65
5. In a machine of the class described, in combination, a roll; internally-located supporting bearing means therefor projecting beyond one end only thereof; a frame; a vertically-disposed arm fixedly associated with said supporting-bearing means and located beyond the inner end of said roll; horizontally-disposed means fixedly associated with the lower end of said arm; a bearing block for each end of said horizontally-disposed means, each bearing block being located in a slotted portion of each end of the frame; means whereby one of said bearing blocks is pivoted in place to one side of the axis of said horizontally-disposed means to permit the same to be moved in a horizontal plane, and pressure-regulating means associated with said other block whereby through the movement of said horizontally-disposed means in a horizontal plane the position of the outer end of said roll with respect to that of said shoe can be regulated. 70
6. In a machine of the class described, in combination, a horizontally-disposed tubular head; a vertically-disposed arm therefor extending therebelow; horizontally-disposed supporting means for said arm, the same lying in the same direction as said head; a frame; a bearing block for each end of said supporting means, each being located in a slotted portion of each end of the frame; means whereby one of said bearing blocks is pivoted in place to one side of the axis of said horizontally-disposed supporting means to permit the same to be moved in a horizontal plane; a coiled spring interposed between said other block and its associated end of said frame; a slotted housing supported by said frame and enclosing the sides of said other block, and through which the outer end of said horizontally-disposed supporting means passes, and an adjusting screw carried by said housing and adapted to exert pressure against said other block and to co-act with said spring whereby said head may be moved in a horizontal plane in 75 80 85 90 95 100 105 110 115 120 125 130

opposite directions around the pivoting means for said first-mentioned block.

7. In a machine of the class described, in combination, a base; a shoe fixedly supported at each end by vertically-disposed members carried by said base, the vertically-disposed supporting member for the outer end of the shoe shaped to allow unobstructed entry to said shoe at this end in a horizontal plane; a roll; internally-located supporting-bearing means for said roll projecting beyond the inner end solely thereof whereby said roll is supported solely from this end of the machine thereby leaving the outer end of the roll permanently uncovered; a driven shaft located within said supporting-bearing means projecting beyond the inner end of said bearing means, and whereby said roll is revolved; means extending from one side of the base to the other and having bearing therein and whereby the said supporting-bearing means is horizontally pivoted in said base below said roll, and means co-acting with said supporting-bearing means and supported by said base

whereby the position of said roll with respect to said shoe can be maintained as desired.

8. In a machine of the class described, in combination, a frame; a shoe fixedly carried thereby; a roll; internally-located supporting-bearing means for said roll projecting beyond the inner end thereof; a vertically-disposed arm carried by said supporting-bearing means and located at the inner end of said roll; a horizontally-disposed member fixedly associated with the lower end of said arm and lying in the same direction as said roll; means whereby the ends of said horizontally-disposed member are journaled in said frame; a hand lever pivoted to a portion of said frame; an arm fixedly secured at its inner end to said horizontally-disposed member; a substantially vertically disposed rod pivoted to the outer end of said hand lever and passing freely through the outer end of said arm; a coiled spring mounted on said rod, and a stop to limit the forward movement of said hand lever.

WILLIAM HENRY SUMBLING.
